Primary Examiner — Sandra S Snapp*Assistant Examiner* — Mehri F Bajoul(74) Attorney, Agent, or Firm — Russell Ng PLLC; Brian F. Russell(57) CLAIM

The ornamental design for an animal toy, as shown and described.

DESCRIPTION

FIG. 1 is a perspective view of the animal toy.

FIG. 2 is a front elevation view of the animal toy.

FIG. 3 is a back elevation view of the animal toy.

FIG. 4 is a left side elevation view of the animal toy.

FIG. 5 is a right side elevation view of the animal toy.

FIG. 6 is a top plan view of the animal toy; and,

FIG. 7 is a bottom plan view of the animal toy.

The broken lines shown in the drawings depict portions of the animal toy that form no part of the claimed design.
